UNITED STATES PATENT OFFICE.

LEWIS W. TRACY, OF PHILADELPHIA, PENNSYLVANIA, ASSIGNOR OF ONE-HALF TO JAMES E. GRANNIS, OF NEW YORK, N. Y.

ELEVATOR.

SPECIFICATION forming part of Letters Patent No. 245,676, dated August 16, 1881.

Application filed March 18, 1881. (No model.)

To all whom it may concern:

Be it known that I, LEWIS W. TRACY, of Philadelphia, county of Philadelphia, State of Pennsylvania, have invented certain new and useful Improvements in Elevators, of which 5 the following is a specification.

This invention relates to the safety-catches of elevators, and has for its object to enable the same to be operated by the attendant to 10 stop the elevator at any point, irrespective of the usual devices designed to actuate the catches automatically when the rope breaks.

It sometimes happens that some part of the hoisting machinery gives way, while the rope 15 or chain remains intact, thereby allowing the elevator to fall with damaging effect, the tension on the rope or chain being sufficient to prevent the draw-bar, to which it is attached, from being operated by its spring to throw the safety- 20 catches out into the rack-bars or other device, secured to the fixed guide-posts of the elevator. From such cause, or from the safety device becoming inoperative, when the rope or chain breaks, from long disuse, accidents may be 25 avoided by the use of my invention, which consists of a hand-lever, within easy reach of the attendant, connected to the links which connect the draw-bar to the safety-catches. Said links, instead of being fastened to the draw- 30 bar by fixed pivots, are pivoted in slots in the draw-bar, so that when the hand-lever is pulled down the safety-catches are moved out to engage the rack-bars or other devices attached to the fixed guide-post without necessitating 35 any movement of the draw-bar, thereby enabling the attendant to instantly stop the elevator-car should it at any time, either from a break of the machinery or an excessive load, acquire a dangerous downward speed. A 40 spring or weighted latch is provided to lock the hand-lever when the safety-catches are thrown out.

To describe my invention more particularly, I will refer to the accompanying drawings, 45 forming part of this specification, in which—

Figure 1 is an elevation of an elevator provided with my invention, partly in section. Fig. 2 is a transverse section of the upper part of the same. Fig. 3 is a plan view, partly in 50 section, and Fig. 4 shows a modification.

In the drawings an ordinary freight-elevator

car, *a*, is shown, sliding between the guide-posts *b b*, which are provided with the ratchet-tooth racks *c c*. In the head *a'* of the car is fitted the draw-bar *d*, provided with the spring *e*, and attached to the rope *f* in the ordinary manner. The safety-catches *g g* are fitted to slide in the head *a'*. On their outer ends are formed two or more teeth, adapted to fit in the teeth of rack-bars *c c* when the slides are 60 moved outward. To the inner ends of these safety-catches *g g* are pivoted the links *h h*, which are connected to the draw-bar *d* by the bolts *i i*, passing through them and through longitudinal slots formed in the draw-bar. 65 These bolts *i i* also connect the plate *j* to the links *h h*, and to the plate *j* is pivoted the hand-lever *k*, which has its fulcrum at *k'* in the head *a'* of the car, and the handle *k²* projects downwardly in the car, within easy reach of the attendant. In the head *a'* is also pivoted the weighted latch or pawl *l*, so constructed and located that when the lever *k* is depressed the pawl *l* falls over the top of it and holds it down. 70 It is obvious that this pawl *l* may be actuated 75 by a spring instead of being weighted.

The spring *m* holds up the hand-lever *k* and keeps the bolts *i i* against the upper ends of the longitudinal slots in the draw-bar *d* when the parts are in their normal positions, so that 80 the catches *g g* may be moved out to engage in the rack-bars *c c* in the ordinary manner by the resilience of the spring *e* should the rope *f* break, in which case the pawl *l* will fall over the top of the lever and hold the safety-catches 85 in the rack-bars.

The modification shown in Fig. 4 consists in providing the latch or pawl *l* with a handle, *l'*, and making the lever *k* without a handle, so that the safety-catches may be moved out 90 by operating the handle *l'* to turn the latch (which may be cam-shaped) down onto the lever *k*, in which position it is shown in the drawings.

It is evident from the foregoing that by depressing the lever *k*, by actuating its handle *k²* or the handle *l'* of the latch *l*, the bolts *i i* will be moved down the longitudinal slots in the draw-bar *d*, and the safety-catches moved out to engage in the rack-bars *c c*, while the 100 draw-bar *d* remains in its normal position.

The drawings show my improvement in safe-

ty-catches for elevators as applied to freight-elevators of ordinary construction. It is obvious that the principle involved in the same may be practically applied to any form of elevator which is provided with a draw-bar adapted to slide in the head of the elevator, by means substantially as above described.

Having now described my invention, what I claim, and desire to secure by Letters Patent, 10 is—

1. The combination of a hand-lever with the one set of safety-catches of an elevator, and means for connecting the safety-catches to the draw-bar by which they are operated when the tension is removed from the hoisting-rope, and at the same time free to be operated by the hand-lever when the draw-bar is in its normal position, substantially as and for the purpose hereinbefore set forth.

2. In an elevator safety device, in combination, a spring-acting draw-bar provided with longitudinal slots, safety-catches fitted in guides at right angles to the draw-bar, connecting-links pivoted at one end on bolts fitted 15 in the longitudinal slots of the draw-bar, and

at their other ends to the inner ends of the safety-catches, and a hand-lever connected to the links and provided with a spring, substantially as and for the purpose hereinbefore set forth.

3. In an elevator safety device, in combination, a spring-acting draw-bar provided with longitudinal slots, safety-catches fitted in guides at right angles to the draw-bar, connecting-links pivoted at one end on bolts fitted 30 in the longitudinal slots of the draw-bar, and at their other ends to the inner ends of the safety-catches, a hand-lever connected to the links and provided with a spring, and a weighted or spring-acting pawl adapted to hold the hand-lever down when depressed, substantially as and for the purpose hereinbefore set forth.

In testimony whereof I have hereunto set my hand this 15th day of March, A. D. 1881.

LEWIS W. TRACY.
